[57] CLAIM

The ornamental design for a drum cover, shown and
described.

DESCRIPTION

FIG. 1 is a front elevational view of a drum cover
showing my new design;

FIG. 2 is a rear elevational view thereof;

FIG. 3 is a right side elevational view thereof, the left
side being a mirror image;

FIG. 4 is a front elevational view of a second embodi-
ment of the drum cover illustrated in FIG. 1;

FIG. 5 is a rear elevational view of the embodiment
disclosed in FIG. 4 and,

FIG. 6 is a right side elevational view of the embodi-
ment disclosed in FIG. 4, the left side being a mirror
image.

FIG. 1

FIG. 2

FIG. 3

FIG. 4
